UNITED STATES PATENT OFFICE

FRANK MASTRANGELO AND ALPHONSE MASTRANGELO, OF FITCHBURG,
MASSACHUSETTS

FOLDING FURNITURE

Application filed October 21, 1929. Serial No. 401,051.

This invention relates to a table and benches adapted to be located in a cabinet built in to the side of a room, or constituting a piece of movable furniture, and to be held normally in vertical position against, or in, the rear wall and doors thereof and to be unfolded into horizontal position ready for use in a very simple manner.

The principal objects of the invention are to provide a compact way of mounting a folding table and benches which can be located, when folded up, in a cabinet built into the wall of a room or can be movable; to provide means whereby the folding of the table and benches can be accomplished in a very simple manner without unhooking any of the parts of the table or the benches and they will be left in vertical position in such condition that when moved outwardly about a pivot they will automatically assume not only the position of a piece of furniture of that kind but their desired relationship to each other and will be braced properly in that position and to provide folding braces by which the furniture is strengthened. The invention is not limited to a table and benches but can be applied to other types of furniture.

Other objects and advantages of the invention will appear hereinafter.

Reference is to be had to the accompanying drawings in which

Fig. 1 is an elevation of a cabinet with the doors open showing a table and a bench on each side of it to hold it up in vertical position;

Fig. 2 is a side view showing in full lines the table when moved down to position for use and also showing an intermediate position in dotted lines;

Fig. 3 is an enlarged sectional view on the line 3—3 of Fig. 2, and

Fig. 4 is a view similar to Fig. 2 showing one of the benches in the two positions corresponding to those shown in Fig. 2.

This set of furniture is shown as "built-in" because it is adapted to be located within the confines of the wall of the room. The back of the cabinet is indicated by a board or the like 10. Some of the uprights are left out, if necessary, and the cabinet 11 intro-

duced into the wall with only the outer molding outside the front surface of the piece 10. This provides a closet or recess in the wall for receiving the furniture when folded back in vertical position. This cabinet has two doors 40. It can be located anywhere in the room also and not built in, if desired.

Referring first to the table, this comprises a top 13 hinged at 14 to a cleat or the like 15 secured in stationary position to the back wall of the cabinet 11. The table top is provided with a leg 16 which may be made in any desired ornamental shape, preferably of wood, and hinged at 17 to the table top near its end. No rear leg is required because the cleat 15 supports the table at the rear. It is desired to brace the top both from the leg 16 and from the rear wall of the cabinet 11. For this purpose a pair of braces 18 and 19 are provided, the brace 18 being hinged inside of the leg 16 at 20 and the brace 19 being hinged at 21 to a base board 22 or to the back of the cabinet 11. The two braces 18 and 19 are also provided with hinges 23 and 24 respectively at their upper ends which are secured to a slide 25. This slide moves in guides which are shown as in the form of two plates 26 arranged horizontally on the under side of the table top 13 and entering longitudinal slots in the sides of the slide.

It will be seen that, as the two hinges 20 and 21 are stationary and as the two hinges 23 and 24 are fixed to the same element 25, the braces effectively support the table near its center in spite of the fact that the slide is free to move in either direction. They constitute supporting struts to hold up the table and yet when the table top is lifted as shown in Fig. 2, these braces are free to swing from the hinge 21 and they themselves, by the fact that the top of the brace 19 must come downwardly with respect to the table top and pull the brace 18 downwardly, fold the leg 16 as the table top swings back. As a matter of fact the leg 16 is always in practically vertical position.

When the table top swings back into contact with the back of the cabinet 11 the parts 18 and 19 will also be vertical and lie against it while the leg 16 will lie down in nearly

vertical position outside the brace 18. When moved back the end of the table top 13 engages a spring catch 28 and is held in behind it as shown in Fig. 2 in dotted lines and the 5 whole device is held in vertical position by that latch.

In order to bring the table back into position for use it is only necessary to draw back the latch by its handle 27 and the table top 10 will swing back, but it is usually pulled back as the operator will keep it under control at all times. It will come down to the full line position as shown in Fig. 2 where, without any manipulation whatever, it is left in 15 position for use and with the braces in position to serve as supports.

The two benches preferably are made just alike and on the same principle as the table. Each bench top 30 is hinged to a door at 20 31 but the benches, instead of having one leg only at the outer end, have two legs 32 and 33, one at each end as the benches have to support a heavier load than the table. In this case the leg 33 is connected by a strut 34 25 hinged at both ends to a door 40. This strut is slightly inclined. Two struts 35 and 36, which in this instance are shown as offset, are hinged to the legs 32 and 33 respectively by hinges 37 and 38 and they are provided 30 with the same slide 25 and the hinges 23 and 24 and the guides 26 as shown in Fig. 2.

It will be obvious from what has been said before that the struts 35 and 36 support the bench in the center and that both legs, being 35 hinged to the top, will swing outwardly in substantially the same manner as the leg 16 in the other case. The position of the parts when folded half way up is shown in dotted 40 lines in Fig. 4. A latch 39 on the door operating just like the latch 28 is employed to hold these parts back in vertical position. The table top in this case rests against the 45 wall of the room and the strut 35 is offset so that the bottom of the leg 32 will lie flat against it. Also the strut 36 is offset as stated so that the leg 33 can come in under it when it is folded back in vertical position. The 50 benches are operated in the same way as the table. These benches are particularly strong 55 on account of the way in which they are braced and they lie practically flat against the inside of the doors when they are folded up.

In both cases the table and benches have substantially the same characteristic and although we have shown a single embodiment 60 of the invention in one sense of the word, the benches do constitute a slight modification. We are aware of the fact that other 65 modifications can be made in the details of construction without departing from the scope of the invention as expressed in the claims. Therefore we do not wish to be limited to the details of construction herein disclosed otherwise than as set forth in the 70 claims, but what we claim is—

1. In a piece of furniture, the combination with a top hinged at its rear end to a vertical support, two legs hinged to the top, each near one end and adapted to extend downwardly to support the top and both being adapted to 70 swing backwardly toward the support from the hinges, of a pair of struts each hinged at its lower end to one of said legs and extending up at an inclination both to a point near the center of the top, hinged means for connecting the rear leg to the support and a slide on the underside of the top to which both of said struts are hinged, whereby when the top is folded up on its hinge into a vertical position the legs will move into a vertical position and 75 also the two struts. 80

2. In a piece of furniture, the combination with a top hinged at its rear end to the inside of a door of a building, two legs hinged to the top, each near one end and adapted to extend 85 downwardly to support the top and both being adapted to swing backwardly toward the door from their hinges, of a pair of struts each hinged at its lower end to one of said legs and extending up at an inclination to a point near the center of the top, a block 90 slideable on the underside of the top to which both of said struts are hinged, a third strut hinged at one end to the same door and at the other end at a higher point to the adjacent leg, whereby when the top is folded up on its hinge into a vertical position the two legs 95 will move into a vertical position and also the two struts and a latch for holding the top against the door and thus holding all parts 100 of the article in vertical position.

In testimony whereof we have hereunto affixed our signatures.

ALPHONSE MASTRANGELO.
FRANK MASTRANGELO.
